UNITED STATES PATENT OFFICE.

BERNARD H. HARTLEY, OF RED HOUSE, WEST VIRGINIA.

KNIFE.

Application filed October 19, 1920. Serial No. 417,892.

To all whom it may concern:

Be it known that I, BERNARD H. HARTLEY, a citizen of the United States, residing at Red House, in the county of Putnam and State of West Virginia, have invented new and useful Improvements in Knives, of which the following is a specification.

This invention relates to pocket knives and has for one of its chief characteristics, the provision of a knife wherein the handle is designed to completely enclose the blades when the latter are in folded position, to the exclusion of dampness and foreign matter which frequently has a detrimental effect upon the blades of the knife.

Another important object of the invention resides in providing the knife with a two part handle, the respective parts being hingedly connected together, the blades pivoted to fold in superimposed relation within one of the parts, and when extended for use clamped between the respective parts of the handle to prevent accidental closing of the blades when the knife is in use.

Another object of the invention resides in the provision of a novel construction of fastening means for holding the respective parts of the handle fixed relatively in normal position whereby the said parts can be readily and easily locked together or released to permit access to the blades as the occasion requires.

The nature and advantages of the invention will be better understood when the following detail description is read in connection with the accompanying drawings, the invention residing in the construction, combination and arrangement of parts as claimed.

In the drawings forming part of this application like numerals of reference indicate similar parts in the several views, and wherein:

Figure 1 is a perspective view of the knife in its normal position.

Figure 2 is a longitudinal sectional view therethrough.

Figure 3 is a plan view of the knife showing the handle opened and the blades in folded position.

Figure 4 is a similar view showing the blades extended for use.

Figure 5 is a view showing the blades in extended position and the sections of the

handle closed to hold the blades immovable. 55

Figure 6 is a sectional view taken on line 6-6 of Figure 5.

Figure 7 is a detail view of the fastening elements separated from the handle of the knife. 60

Referring to the drawings in detail, 10 and 11 indicate the respective parts of the handle of the knife, the former being hollow to accommodate the blades and also open at both ends thereof as at 12. The section or 65 part 11 constitutes a cover or closure for the hollow portion 11 to which it is hingedly secured as at 13. The blades of the knife are indicated at 14 and have their corresponding extremities pivoted between the sides of the 70 member 10 of the handle so that the blades can be swung toward each other in overlapped relation and folded within the member 10 of the handle, or projected through the opened ends of the member 10 and extended to a position for use. When the 75 blades are in an extended position, they lie below the upper surface of the member 10, this providing a space or pocket for the reception of the enlargement 15 formed at the 80 ends of the under side of the member 11 of the handle. Consequently, when this member 11 is folded upon the member 10, with the blade in an extended position, the enlargements 15 repose upon the blade and 85 serve to effectively retain the latter in an extended position and against any relative movement with respect to each other or regard to the handle in its entirety. The knife can thus be used in the usual manner without any possibility of the blades accidentally closing. When the blades are folded in superimposed relation within the member 10 90 of the handle the member 11 arranged in its normal position, the blades are completely 95 housed and enclosed between the respective members of the handle, to the exclusion of the dirt and dampness, which usually has a bad effect upon the blades.

In order to secure the respective members 100 of the handle together, I preferably make use of a slide such as indicated in Figure 7, the slide comprising two parallel members 20 and 21 respectively these members being arranged at the opposite sides of the back 105 wall of the member 10 of the handle. These members are connected together by the stem 22 and one of these members which may be

termed a manipulating member is provided with a head 23. The rear wall of the member 10 of the handle upon which the slide is mounted, is provided with an elongated notch or recess 24 in which the manipulating member of the slide operates. One of the parallel members 20 of the slide is formed with inwardly directed flanges 25 arranged in spaced relation, while one edge of the member 11 of the handle is provided with notches 27, there being one of these notches for each of the flanges referred to which receives the flanges when the slide is in one position. The notches 27 also communicate with the slots 28 formed in the edge of the member 11 so that subsequent to positioning the flanges within the notches, and moving the slide longitudinally of the handle, the flanges are positioned within the notches 29 and thereby hold the respective members of the handle fixed relatively. The construction is very simple and consequently the slide can be readily and easily manipulated to either lock the members of the handle fixed relative or release the same to permit access being had to the blades 14. The component parts of the knife can be constructed of any suitable material, while the knife itself may vary in size and configuration without departing from the spirit of the invention.

While it is believed that from the foregoing description the nature and advantages of the invention will be readily apparent, I desire to have it understood that I do not limit myself to what is herein shown and described and that such changes may be re-

sorted to when desired as fall within the scope of what is claimed.

What I claim is:

A pocket knife of the character described comprising a sectional handle hingedly connected together, one of said sections being hollow and open at both ends, blades pivoted within the hollow section and being adapted to be folded therein in superimposed relation, said blades lying below the upper surface of the hollow section and providing a space on the outer side of their pivotal connection with the hollow section, an enlargement formed at each end of the opposite section of each handle and being adapted to be received in the respective spaces, a slide for connecting the sections together when folded and including spaced parallel members arranged on opposite sides of the free side of the hollow section, a stem connecting the parallel members for cooperative movement, the side wall of the hollow portion being provided with an elongated recess through which the parallel members slide, a head projecting from the outer parallel member and adapted to facilitate the operation of the slide, spaced flanges formed on the outer parallel member and being adapted to be received in notches formed on the opposite handle portion, said notches communicating with slots so that the flanges may be positioned within the slots to hold the respective members of the handle relatively fixed.

In testimony whereof I affix my signature.

BERNARD H. HARTLEY.
